Specification of Letters Patent. Patented Oct. 21, 1919.

Application filed January 23, 1919. Serial No. 272,660.

To all whom it may concern:

Be it known that I, ALBERT BENZINGER, a citizen of the United States, and a resident of Cincinnati, in the county of Hamilton and State of Ohio, have invented certain new and useful Improvements in Radiators, of which the following is a specification.

My invention relates to cooling devices and more especially to radiators for explosive engines, and its object is to afford a more efficient radiating surface and more elasticity of the structure under disrupting influences, such as freezing, and at the same time simplify the construction and maintenance of the device. Other objects will appear in the ensuing description.

My invention consists in the combination of parts and in the details of construction and arrangement of parts as will herein-after be more fully described and claimed.

In the drawings:

Figure 1 is a general perspective view of a radiator constructed according to my invention;

Fig. 2 is a sectional plan view of the same;

Fig. 3 is a vertical front-to-rear section on a plane corresponding to the line 3—3 of Fig. 1;

Fig. 4 is a detail inverted plan view of the top;

Fig. 5 is a detail plan view of the bottom;

Fig. 6 is a partial section corresponding to Fig. 3, enlarged, showing the preferred formation and junction of the plates;

Fig. 7 is a view similar to Fig. 6 showing a modification; and

Figs. 8 and 9 are partial front elevations showing modified patterns of embossing in the plates.

As I prefer to construct my improved radiator, it comprises the top 1 and bottom 2, each suitably constructed of sheet metal whereby it is of hollow formation; these being joined by upright lateral parts 3, which together with the top 1 and bottom 2 constitute an outer framework for the radiator. This framework near its bottom preferably has the laterally projected lugs 4 by means of which it is attached to the frame of the vehicle or engine or other device in connection with which the radiator is used. The inlet nipple 5 leads into the lower rear part of the top 1, and the outlet nipple 6 leads from the lower part of the

bottom 2 rearwardly and has the drain-cock 7. Also, the top 1 has the neck 8 suitably provided with a cap 9 which, upon removal, permits of filling the cooling apparatus with water or other cooling medium. 60

Occupying the space within the framework made up of the details just described, are the radiator cores 10 having hollow interiors communicating with the interiors of the top 1 and bottom 2, so that water or other cooling medium entering the top 1 passes down through the cores 10 and is cooled by contact with the inner surfaces of the cores and then passes into the bottom 2 and out through the outlets 6. It will be 70 understood that suitable connections are made between the outlet 6 and inlet 5, so that a constant circulation of the cooling medium is maintained through the water jackets of the engine or the corresponding 75 cooling apparatus of any other devices required to be cooled.

Each one of the cores or units 10 is made up of two thin metal sheets 11 and 12. Each one of these sheets has a plurality of 80 holes punched in it and from each hole is pressed out a short neck 13 or 14, respectively. These necks 13 and 14 are integral with the metal of the respective sheets. Each such hole and its accompanying neck 85 13 or 14 is surrounded by an annular boss 15 or 16 pressed out from the sheet 11 or 12, respectively, on the side opposite from that where the neck 13 or 14 extends.

The holes and the accompanying necks 13 90 and 14 and bosses 15 and 16 being of a circular pattern, as shown in Figs. 1 to 6, spaces are left between each adjacent four bosses 15 and 16 in the respective sheet 11 or 12, and, preferably, in these spaces small round 95 bosses 17 or 18, respectively, are pressed out on the sides where the necks are.

The neck 13 of the sheet 11 is somewhat longer than the neck 14 of the sheet 12, but is of less diameter in such degree that it snugly 100 fits inside the neck 14. The two sheets thus formed are brought together so that all of the necks 13 of the sheet 11 pass through the necks 14 of the sheet 12 until the ends of the necks 14 come against the adjacent side of 105 the sheet 11 around the respective necks 13. These necks 14 thus form spacing elements between the two sheets. Thereupon, the protruding ends of the necks 13 are flanged out and down against the outer surface of the 110

sheet 12. This fastens the two sheets securely together. The lugs 17 and 18, by this relation of the sheets, are brought together and also form spacing elements between the 5 two sheets 11 and 12.

Where the inner sleeve 13 is thus flanged out tightly against the other sheet 12, the joint is soldered; and the solder may be sweated in between the two necks 13 and 14. 10 This strengthens the structure and makes it watertight at these joints. Preferably, the sheets are tinned on their inner sides before being put together, thus insuring the success of the soldering. Also, each one of the 15 flanged necks 13 being entirely surrounded by one of the annular bosses 16, a narrow annular basin is thus constituted entirely around adjacent to the flange so that the solder is held thereto in considerable quantity 20 and the soldered joint is thus made very heavy and substantial.

These just described details are especially clearly shown in Fig. 6 of the drawings.

The lateral edges of the plates are preferably secured together as shown in the left-hand sectional part of Fig. 2. The sheet 12 has its edge part 19 turned back and then a flange 20 of this part is turned laterally outwardly. Over this flange 20 is seamed the 25 edge part 21 of the other sheet 11; and then, preferably, this seam is again turned inward against the outside of the part 19 of the sheet 12, forming a double seam 22 along each vertical edge of the core or unit 10. This seam. 30 is soldered in the usual manner. Such a junction of the plates at their lateral edges greatly reinforces them thereat; but it will be understood that any suitable liquid-tight and properly reinforcing construction may 35 be provided in these parts of the core or unit.

The tops 23 and bottoms 24 of the respective units 10 are left open to the extent provided by the spacing afforded by the necks 40 14 and bosses 17 and 18. The top 1 of the radiator has the transverse slots 25, and the bottom 2 has the transverse slots 26 (Figs. 4 and 5.) Into these slots 25 and 26 are inserted the upper and lower ends, respectively, of the respective units 10, so that the edge parts of the sheets 11 and 12 project some distance above the inner surfaces of the slotted parts, whereupon these edge parts are flanged over and soldered. These junctions 50 are clearly shown in Fig. 3.

I prefer to give to the top 1 of the radiator a forwardly swelled formation at its middle, as indicated in Figs. 1 to 4; this design of the radiator top being very much in 60 favor, not only on account of its ornamental appearance, but on account of the added radiating surface afforded within a given width permitted for the radiator on a vehicle. Usually where the top is thus or similarly formed, the bottom is correspondingly 65

formed, as is also the core from top to bottom. My improved construction lends itself to very desirable modifications from this ordinary design. Thus, as indicated in Figs. 1 to 4, the bottom 2 is straight from side to 70 side and the units 10, while having their upper edges bent to follow the curved formation of the slots 25 which are parallel with the curved front of the radiator top 1, have this curvature gradually modified from 75 their tops to their bottoms until, when they reach the bottom 2 they are straight and conform to the straight slots 26 of the bottom 2. It will be understood that other designs involving this shaping of the units 10 may be 80 adopted as may suit the fancy or requirements of the builder. But in any instance there is a practical advantage in having the top of the radiator more extended than the bottom. This is because the radiator is always 85 hotter at the top than at the bottom. If freezing of the radiator takes places it begins at the bottom. Where the radiating capacity of the top and bottom are substantially the same, it may very well be that in 90 extremely cold weather the bottom of the radiator would begin to freeze while the no-more-extended top is not too cool. With more radiating surface at the top than at the bottom, the two parts of the radiator will 95 function more nearly alike and in many instances overheating in the one or freezing in the other will be avoided.

In Fig. 8 the openings and the surrounding necks are circular, but the embossing 10 that surrounds these openings and necks is in the form of straight ridges 16' running diagonally of the sheet and crossing each other at right angles between the openings and necks 13; thus leaving the basin around 11 each flanged neck 13 square. In this example, the embossing thus occupies almost all of the space between each four adjacent openings and the bosses 17 and 18 are not used. It will be understood that Fig. 8 represents the front plate 12' of one of these modified units 10'; but it will be understood that the embossing on the other plate, corresponding to the embossing 15 on the plate 11, would be of the same pattern as that 1 shown in Fig. 8.

In the other modification in Fig. 9, the openings and their surrounding necks 13 are also round, but the bosses 16'' are four-sided figures with their sides curved inward and 1 having the corners curved; this being an example of ornamental design to which my improved construction is readily adapted. It will be understood that any other fanciful design may be adopted; even more intricate 1 embossing than that here shown being possible if desired.

In any of these cases where the telescoping necks 13 and 14 are used so that the sheets are materially spaced apart, the in- 1

terior circulating space for the cooling medium is ample, and is especially wide immediately adjacent to the openings and their necks 13 and 14. The object is to have a flow of air through the openings and necks 13 which may thus come in very close proximity to the contained water or other cooling medium as it passes around the neck 14. The free flow of the cooling medium therearound is facilitated by the ample space afforded by the bosses 15 and 16, and the increased surfaces formed by these embossings further contribute to the cooling effect. Where the inner bosses 17 and 18 are used, as in Figs. 3 and 6, these, in addition to spacing the sheets apart as before described, act as baffles to cause the water or other medium to splash in various directions into the adjacent enlarged spaces between the bosses 15 and 16 and around the necks 14. In the examples of Figs. 8 and 9 with these bosses 17 and 18 absent, this splashing effect is not so pronounced; but it will be seen that the diagonal arrangement in Fig. 8 and the 25 sinuous arrangement of the most closely adjacent parts of the plate in Fig. 9 will function very much in this manner. Also, it will be understood that any of these modified designs may have such elements as the 30 bosses 17 and 18 incorporated in them.

In the modification shown in Fig. 7, the sheets 11^a and 12^a have openings, but the sheet 12^a has no neck 14 to form a spacing element. The sheet 11^a has the neck 13^a which passes through the opening in the sheet 12^a and is flanged outwardly against the front surface thereof. These parts are surrounded by the bosses 15^a and 16^a in the respective sheets, and also have the inner bosses 17^a and 18^a. It will be understood that these details will function as in the previous examples; but the air passing through the opening within the neck 13^a cannot come so close to the contained cooling element as where only the comparatively thin telescoping walls 13 and 14 intervene as in the previous example. Here, there is interposed a comparatively great annular extent of the sheet metal presented edgewise. Therefore, this construction is not so efficient; and the capacity is not as large for sheets of a given size. It is cited as another example conforming to the principle of my invention.

55 In any of the examples, it is preferable that the units 10 be arranged so that their front-to-rear openings for the passage of air are in alinement, as clearly shown in Figs. 2 and 3. This permits ready access to any 60 one of the openings in any one of the units through the openings of the intervening units. This is very desirable for repairing any of the joints around these openings. Where the upper part of the radiator has 65 the curved formation as shown, the openings

in the upper parts of the units will not be strictly in front-to-rear alinement; but the alinement will be sufficient for the practical purposes just mentioned.

I have found by actual experiment that 70 the radiator core made up of very thin sheet metal and constructed as hereinbefore described withstands freezing entirely satisfactorily. This is because of the elasticity afforded by the embossed construction of the 75 several sheets which permits them to readily spread apart under the freezing action; and also to the extremely strong joint formed between the sheets, as by the telescoping flanged and soldered necks 13 and 14, or the 80 flanged and soldered construction shown in Fig. 7. The former is especially strong because of the comparatively great extent of intimately contacting surfaces of the two sheets around the necks, as well as at their 85 flanged junction, which thus reinforce each other very materially, even aside from the very effective soldering that may be effected throughout these extensive surfaces.

Notwithstanding the considerable degree 90 of embossing, and the intricacy of travel which the cooling medium must undergo, which thus facilitates the cooling and guards against disruption, there is no objectionable obstruction to encourage the collection of 95 sediment at any place in the radiator.

While certain constructional details are deemed preferable in connection with my invention, and I have shown and described these rather specifically in elucidating the 100 construction and use of my invention, as is required, I do not wish to be understood as being limited to such precise showing and description, but having thus fully described my invention, what I claim as new and de- 105 desire to secure by Letters Patent is:

1. In a radiator, two sheets, each having a plurality of openings, said sheets having their edge parts suitably joined, and each one of said openings of one sheet being substantially coincident with a respective opening of the other sheet, one of each two coincident openings having a neck therearound projected through and flanged out around the edge of the coincident opening in the 110 other sheet, and one of said sheets having parts embossed outwardly on its side remote from the other sheet around and between said openings.

2. In a radiator, two sheets, each having 115 a plurality of openings, said sheets having their edge parts suitably joined, and each one of said openings of one sheet being substantially coincident with a respective opening of the other sheet, one of each two coincident openings having a neck therearound projected through and flanged out around the edge of the coincident opening in the other sheet, and each one of said 120 sheets having parts embossed outwardly on its side remote from the other sheet around and between said openings.

from its side remote from the other sheet around and between said openings.

3. In a radiator, two sheets, each having a plurality of openings, said sheets having 5 their edge parts suitably joined, and each one of said openings of one sheet being substantially coincident with a respective opening of the other sheet, one of each two coincident openings having a neck there- 10 around projected through and flanged out around the edge of the coincident opening in the other sheet, one of said sheets having parts embossed outwardly on its side remote from the other sheet around and 15 between said openings, and one of said sheets having parts embossed inwardly toward the other sheet between said outwardly embossed parts.

4. In a radiator, two sheets, each having 20 a plurality of openings, said sheets having their edges suitably joined, and each one of said openings of one sheet being substantially coincident with a respective opening in the other sheet, each sheet having a 25 neck around each one of its openings, and the neck of each opening of one sheet being of less diameter than the neck of the coincident opening in the other sheet, and being projected through said neck and opening 30 of the other sheet and flanged out around the edge of said coincident opening in the other sheet, with the neck of that opening forming spacing means between the two sheets around the neck that projects through 35 it, and one of said sheets having parts embossed outwardly on its side remote from the other sheet around and between said openings.

5. In a radiator, two sheets, each having 40 a plurality of openings, said sheets having their edges suitably joined, and each one of said openings of one sheet being substantially coincident with a respective opening of the other sheet, each one of said 45 sheets having necks around the respective openings thereof, the necks of one sheet being of less diameter than the necks of the other sheet, and being projected through said necks of the other sheet and flanged 50 out around the edge of the coincident opening in the other sheet, and one of said sheets having parts embossed outwardly on its side remote from the other sheet around and between said openings.

55 6. In a radiator, two sheets, each having a plurality of openings, said sheets having their edges suitably joined, and each one of said openings of one sheet being substantially coincident with a respective opening 60 in the other sheet, each sheet having a neck around each one of its openings, and the neck of one of each two coincident openings being of less diameter than the neck of the coincident opening in the other sheet, 65 and being projected through said neck and

opening of the other sheet and flanged out around the edge of said coincident opening in the other sheet, with the neck of that opening forming spacing means between the two sheets around the neck that projects through it, one of said sheets having parts embossed outwardly on its side remote from the other sheet around and between said openings, and one of said sheets having parts embossed inwardly toward the other sheet between said outwardly embossed parts.

7. In a radiator, two sheets, each having a plurality of openings, said sheets having their edges suitably joined, and each one 80 of said openings of one sheet being substantially coincident with a respective opening of the other sheet, each one of said sheets having necks around the respective openings thereof, the necks of one sheet being of less diameter than the necks of the other sheet, and being projected through said necks of the other sheet and flanged out around the edge of the coincident opening in the other sheet, one of said sheets 90 having parts embossed outwardly on its side remote from the other sheet around and between said openings, and one of said sheets having parts embossed inwardly toward the other sheet between said outwardly 95 embossed parts.

8. In a radiator, two sheets, each having a plurality of openings, said sheets having their edges suitably joined, and each one of said openings of one sheet being substantially coincident with a respective opening in the other sheet, each sheet having a neck around each one of its openings, and the neck of each two coincident openings being of less diameter than the neck 105 of the coincident opening in the other sheet, and being projected through said neck and opening of the other sheet and flanged out around the edge of said coincident opening in the other sheet, with the 110 neck of that opening forming spacing means between the two sheets around the neck that projects through it, and each one of said sheets having parts embossed outwardly on its part remote from the other 115 sheet around and between said openings.

9. In a radiator, a hollow top and a hollow bottom, and a plurality of conducting and radiating elements extending from said top to said bottom, and each communicating with the interiors of said top and bottom, each one of said elements having a plurality of openings through it around which its hollow interior is disposed, said elements being curved at their junctions with said top, 120 and the degree of their curvature gradually decreasing toward said bottom.

10. In a radiator, a hollow top having a plurality of transverse slots in its bottom succeeding from front to rear thereof, and 130

- a hollow bottom having a plurality of transverse slots in its top succeeding from front to rear thereof, and a plurality of radiating and conducting units each made up of two sheets, each sheet having a plurality of openings, said sheets having their edges suitably joined, and each one of said openings of one sheet in a unit being substantially coincident with a respective opening of the other sheet of the unit, and one of each two coincident openings having a neck therearound projected through and flanged out around the edge of the coincident opening in the other sheet, and parts of said sheets being in spaced-apart relation whereby circulating spaces are formed in each unit around its opening, and the upper and lower edge parts of the sheets of each unit being projected through a respective slot in said top and said bottom, respectively, said slots in the bottom of said top being curved, and the sheets of the respective units being correspondingly curved in their extension through said slots, but gradually decreasing in curvature toward said bottom.
11. In a radiator, a hollow top having a plurality of transverse slots in its bottom succeeding from front to rear thereof, and a hollow bottom having a plurality of transverse slots in its top succeeding from front to rear thereof, and a plurality of radiating and conducting units each made up of two sheets, each sheet having a plurality of openings, said sheets having their edges suitably joined, and each one of said openings of one sheet in a unit being substantially coincident with a respective opening of the other sheet of the unit, and one of each two coincident openings having a neck therearound projected through and flanged out around the edge of the coincident opening in the other sheet, the parts of said sheets being in spaced-apart relation whereby circulating spaces are formed in each unit around its opening, and the upper and lower edge parts of the sheets of each unit being projected through a respective slot in said top and said bottom, respectively, the necks and openings of each one of said units thus made up being in substantial front-to-rear alinement with respective necks and openings in each one of the other units of the radiator, said slots in the bottom of said top being curved, and the sheets of the respective units being correspondingly curved in their extension through said slots, but gradually decreasing in curvature toward said bottom, the alinement of said necks of the several units near the bottom being substantially from front to rear, but the alinement of said necks in said units near the top being along lines increasingly diverging toward the top.
12. In a radiator, an upright conducting and radiating element, having a plurality of openings through it around which its hollow interior is disposed, and having interior enlarged spaces adjacent to and around said openings, and baffles in said interior adjacent to respective enlarged spaces to cause a liquid cooling medium in said interior to splash in various directions into said enlarged spaces and around said openings.
13. In a radiator, an upright conducting and radiating element having a hollow interior, and having a plurality of necks extending across said hollow interior with the interiors of said necks communicating with the exterior of the element and constituting openings through said element around which the hollow interior of said element is disposed, and said interior of said element having enlarged spaces adjacent to and around respective ones of said necks for the free passage of a cooling medium against and around said necks.
14. In a radiator, an upright conducting and radiating element having a hollow interior, and having a plurality of necks extending across said hollow interior with the interiors of said necks communicating with the exterior of the element and constituting openings through said element around which the hollow interior of said element is disposed, said interior of said element having enlarged spaces adjacent to and around respective ones of said necks for the free passage of a cooling medium against and around said necks, and a plurality of baffles in said interior of said element adjacent to respective ones of said enlarged spaces to cause said cooling medium to splash in various directions into said enlarged spaces and around said necks.
15. In a radiator, an upright conducting and radiating element having a plurality of openings through it around which its hollow interior is disposed, means whereby a liquid cooling medium is conducted into said element in its upper part, and means whereby said medium escapes from said element in its lower part, said element being transversely curved in its upper part with the curvature thereof gradually decreasing toward its lower part, and said element having a plurality of openings through it around which its hollow interior is disposed, these openings being distributed throughout said upper curved part and said lower part and throughout the region of gradually decreasing curvature.

ALBERT BENZINGER.
